AUTOMATIC FURNACE

Nathan M. Lower, Erie, Pa.

Application May 17, 1938, Serial No. 208,381

7 Claims. (Cl. 110—105.5)

This invention relates to automatic stoking mechanism.

One object of the invention is to provide a simple and efficient stoking mechanism capable of feeding fuel to a plurality of furnaces.

Another object of the invention is to provide a simple and efficient mechanism for delivering fuel to a plurality of furnaces and for removing the ashes from a plurality of furnaces and operating said fuel feeding means and said ash removing means in timed relation.

A further object of the invention is to provide in a stoker feeding fuel to a plurality of furnaces, novel and simple means for independently varying the quantity of fuel delivered to each of the furnaces.

A still further object of the invention is to provide simple and efficient mechanism for removing ash from a plurality of furnaces that takes up a minimum of space above the furnace room floor.

With the above and other objects and advantages in view, the invention consists in the features of construction, the combination of elements and arrangement of parts hereinafter more fully described and claimed, and illustrated in the accompanying drawings, in which

Fig. 1 is a front elevation of a furnace installation showing the novel fuel feeding and ash removing mechanism applied thereto, parts being broken away and shown in section;

Fig. 2 is a side elevation of the furnace installation showing the novel fuel feeding and ash removing mechanism applied thereto, parts being broken away and shown in section;

Fig. 3 is a horizontal sectional view through the furnace installation partially through the ash pit to show the ash conveying mechanism and partially at a higher elevation to show the fuel feeding mechanism;

Fig. 4 is a fragmentary sectional view on the line 4—4 of Fig. 1;

Fig. 5 is a fragmentary sectional view on the line 5—5 of Fig. 4, parts being broken away;

Fig. 6 is a fragmentary front elevation of a furnace installation showing the mechanism for operating a modified form of fuel distributing apparatus;

Fig. 7 is a fragmentary sectional view on the line 7—7 of Fig. 6, showing the modified form of fuel distributing mechanism;

Fig. 8 is a fragmentary sectional view on the line 8—8 of Fig. 7 with the firedoor removed; and

Fig. 9 is a fragmentary sectional view on the line 9—9 of Fig. 6.

In the drawings is shown a pair of furnaces 10,

each being provided with a pair of retorts 11 having grates 12. The upright walls 13 of the furnaces are in a common plane and each is provided with a pair of openings 14, above the level 5 of the grates 12, providing access to the retorts 11. Firedoors 15 hinged at 16 form closures for each of the respective openings 14. The furnaces are provided with longitudinally extending trough-like ash pits 17, one beneath each of the 10 retorts 11, formed by the sloping walls 18, extending preferably beneath the level of the furnace. Clean-out doors 20 are provided permitting access to the ash pits 17.

A stoker is provided for mechanically delivering fuel from a source of supply (not shown) to the retorts 11. The stoker includes a horizontal conduit 21, preferably disposed below the level of the furnace room floor 19, leading from the source of fuel supply to one side of the furnace. 15 At its end adjacent the furnace, the conduit 21 communicates with the lower end of a riser conduit 22 that extends upwardly along the furnace side wall 23 to a position immediately forward of the plane of the furnace wall 13 and immediately below the level of the openings 14. A screw conveyor 24 conveys fuel through the conduit 21 and a screw conveyor 25 elevates the fuel through the riser conduit 22. Spaced from and extending horizontally along the furnace walls 13 subjacent the openings 14 therein is a conduit 26. The adjacent ends of the conduits 22 and 26 are provided in their respective side walls with openings and a connecting conduit 27 provides communication between the conduits 22 and 26 through their respective side openings. A screw conveyor 28 conveys fuel through the conduit 26.

The conduit 26 is provided with laterally projecting chambers 29, one subjacent each of the openings 14, into which chambers fuel is delivered by the screw conveyor 28. The chambers 29 open upwardly at about the level of the bottom of the openings 14 and the bulged portion 30 of each of the doors 15 forms a hood over a respective chamber 29. A short vertical screw conveyor 31 is mounted in each of the chambers 29 elevating fuel therethrough and forcing it through the hood portion 30 above the chambers and into the furnace openings 14. If at times fuel accumulates at the end of the conduit 50 26 by reason of failure of one or more of the vertical screw conveyors 31 or for some other reason, the plunger 150 is forced to the left against the pressure of the spring 151, moving the lever 152 which is connected to a circuit breaker 153 for stopping the motor that drives

the stoker. A trap door 154 is provided, so that the accumulated coal may be removed and the plunger will be permitted to resume its original position.

At their upper edges each of the chambers 29 is provided with a horizontal plate-like distributor table 32 extending into a respective opening 14 closely adjacent the lower margin thereof, arranged to receive fuel from the chambers 29. The distributing tables 32 are each provided at their respective rearward central portions with a raised portion 33 extending above the fuel receiving surface of the table, in which there is formed a chamber 34 arranged to receive fluid under pressure from a suitable source of supply. The front face 35 of the raised portion 33 is preferably arcuate in shape and is provided with laterally spaced jet openings 36 communicating with the pressure fluid chamber 34 and directed across the surface of the table 32. Curved upstanding ribs 37 are provided at the forward end of the table 32, arranged to deflect a portion of the projected fuel to the rear corners of the retorts.

With the above construction and arrangement of parts fuel may be mechanically delivered to the retorts with practically no obstruction in the firing opening. The firedoors can be opened and access to the firebox had for purposes of inspection or repairs without disturbing or dismantling any part of the stoking mechanism.

Immediately in front of the furnaces a depression is formed in the furnace-room floor forming a compartment 38. The portion of the trough-like ash pits 17 beneath the level of the furnace-room floor open into the compartment 38. Short horizontal longitudinally extending conduits 39 form continuations of the ash pits 17 and extend into the compartment 38. A screw conveyor 40 is mounted in each of the ash pits 17 and extends into the conduit 39, conveying the ash from the pits 17. The conduits 39 are provided with downwardly opening discharge outlets 41 opening into a horizontal trough 42 disposed in the compartment 38. A screw conveyor 43 in the trough 42 conveys the ash to the base of the riser conduit 44. The riser conduit 44 extends upwardly above the level of the floor at one side of the furnace 10 and a screw conveyor 45 elevates the ash through the riser conduit 44. At its upper end the riser conduit 44 is provided with a downwardly opening spout 46 through which the ash drops into an ash receptacle 47.

The ash conveyor and the stoker fuel conveyor are operated from the same source of power, a motor 48, and their operation is thus in timed relation. The motor 48 is mounted in a compartment 49 disposed at one side of the furnace beneath the level of the furnace room floor. Mounted in the compartment 49 is a longitudinally extending shaft 50 connected at one end with the motor 48 through a speed reducer 51. On the shaft 50 is keyed a worm 52 meshing with a worm gear 53 mounted on the shaft extension 54 of the screw conveyor 24 for operating the latter.

On the same shaft 50 is keyed a second worm 55 which meshes with a worm gear 56 mounted on the lower shaft extension 57 of the fuel elevating screw 25, operatively connecting the elevating screw 25 with the shaft 50. The adjacent ends of the elevating screw 25 and horizontal screw 28 are provided with the shaft extensions 58 and 59, respectively, projecting exteriorly of the conduits housing the screw conveyors. A worm gear 60 on the shaft extension 75

58 engages a worm 61 on the shaft extension 59 for operating the screw conveyor 28.

On the shaft extension 59 there is also mounted a gear 62 meshing with a gear 63 mounted on a horizontal shaft 64 extending transversely of the furnace front wall beneath the conduit 26 operatively connecting the shaft 64 with the horizontal screw 28. On the shaft 64 and adjacent each of the chambers 29 are mounted the worms 65 engaging the worm gears 66 in housings 67 at the base of the chambers 29 for operating the vertical screw sections 31.

In the compartment 49, offset laterally and below the level of the shaft 50, there is mounted 15 a shaft 75, its rearward end being beneath the level of the forward end of the shaft 50. On the adjacent offset ends of the shafts 50 and 75 are mounted the sprocket wheels 76 and 77, respectively, over which passes a sprocket chain 20 78, for driving the shaft 75 from the shaft 50. On the opposite end of the shaft 75 is mounted a worm 79 meshing with a worm gear 80 mounted on the shaft extension 81 of the ash conveying screw 43 for operating the latter. Mounted on 25 a shaft extension 82 of the opposite end of the ash conveying screw 43 is a sprocket wheel 83. A shaft 84 is mounted in the compartment 38 above the level of the trough 42 and at the same level as the ash conveying screws 40 and has 30 mounted thereon at one end a sprocket wheel 85. A sprocket chain 86 passes over the sprocket wheels 83 and 85 operatively connecting the shaft 84 with the ash conveying screw 43.

Mounted on the shaft 84 are a plurality of 35 bevel gears 87 meshing with bevel gears 88 on the extensions 89 of the ash conveying screws 40 for operating the latter. On the shaft 75 between the worm 79 and the sprocket wheel 77 is mounted a worm 90 engaging a worm gear 91 mounted on the lower shaft extension 92 of the ash elevating screw 45, operatively connecting the screw 45 with shaft 75.

The amount of fuel delivered to the retorts 11 may be varied by raising and lowering the vertical 45 screw sections 31, and means, best shown in Fig. 4, is provided for raising and lowering the screw sections 31 independently of each other whereby the amount of fuel delivered to the retorts may be independently varied. It is well known that a screw conveyor working in a horizontal conduit will have a greater conveying action along one side of its axis than the other. Referring to Fig. 5, the screw conveyor 28, when viewed from the right, rotates in a counter-clockwise direction 55 and conveys more coal along the side of the conduit 26 near the chambers 29. The screw conveyor 28 exerts the greatest pressure against the fuel near the bottom of the conduit 26 and the bottom of the chambers 29, since at successively higher elevation there is a greater tendency for the coal to ride over the hub of the horizontal screw 28 away from the vertical screws 31. Thus, with the vertical screws 31 in their lowest position, as shown in Fig. 4, the coal will be compacted between the lowest full turn of the flights thereof, and as the vertical screws are raised from the zone of greatest pressure against the fuel, the coal will be less compacted between the flights and less coal will be discharged onto the plate 32. The gear 66 is keyed to a bearing 93 mounted in the housing 67. A square shaft extension 94 of the vertical screw section 31 extends through a square hole in the bearing 93 so that the shaft extension 94 can be raised or lowered while main-

taining the gear 66 and the vertical screw section 31 in driving engagement. For the purpose of raising and lowering the screw section 31, a threaded tap bolt 95 is provided which is threaded through a bracket 96 fixed to the furnace wall. One end of the tap bolt 95 is secured to the lower end of the square shaft extension 94 while the other end carries a knob 97 for turning the tap bolt 95. Thus by threading the bolt 95 in or out of the bracket 96, the square shaft 94 and hence the screw 31 may be raised or lowered.

In Figs. 6, 7, 8 and 9 is shown a modification of the fuel distributing mechanism of the stoker installation. As in the preferred form of the invention, a conduit 100 extends transversely along the upright walls 101 of a plurality of furnaces 102 at the bottom of the firing openings 103, and a screw conveyor 104 advances fuel therethrough. Also as in the preferred form, discharge conduits 105 preferably formed integral with the conduit 100 are arranged to receive fuel from the conduit 100 and screw conveyors 106 elevate the fuel to the firing openings 103. From the open upper end of the discharge conduits 105, the fuel is forced through a short elbow 107, which is formed with the firedoor 108, and is discharged therefrom in the firing opening.

A nozzle block 109 is mounted adjacent the bottom of the firing opening 103 between the discharge conduit 105 and the furnace wall 101. The nozzle block 109 is provided with a ledge 111 on which is seated a trough 112 arranged to receive fuel from the elbow 107. The trough 112 has a depending annular boss 113 fitting within an annular recess 114 in the ledge 111 whereby the trough 112 may swing in an arc about a vertical axis. Means, to be described later, are provided for continuously oscillating the trough 112.

The trough 112 is preferably horse-shoe shaped in horizontal cross section, and includes in addition to the bottom wall 115, the upstanding curved outer wall 116. Fuel is projected from the trough 112 in aerial paths over the firebed by fluid under pressure issuing through the jet openings 117, from the chamber 118, which is formed in the upstanding trough wall 116. Fluid under pressure passes from a suitable source of supply through the supply pipe 119 to the nozzle block 109 and thence to the chamber 118 by the passages 120, 121 and 122 formed in the nozzle block 109, ledge 111, the boss 113 and trough bottom wall 115, respectively.

The fuel conveying screw 104 and the ash conveying screw 124 are operated from the same source of power as in the preferred form of the invention, and the shaft 125, as in the preferred form is operated from the ash conveying screw. In the modified form of the invention, the means for oscillating the trough 112 is operated from the shaft 125, thus coordinating the rapidity of oscillation of the trough 112 with the speed of the fuel conveying screw.

Fixed to the ash trough 126 is a bearing 127 in which is mounted a short longitudinally extending shaft 128. The shaft 128 carries at one end a bevel gear 129 meshing with a bevel gear 130 mounted on the shaft 125 whereby the rotary motion is transmitted to the short shaft 128. At its other end, the short shaft 128 carries a disk 140, through which near its periphery is threaded a tap bolt 131 extending beyond the outer face of the disk. The projecting portion of the tap bolt engages a slot 132 in a lever 133, pivotally mounted at its lower end, as at 134. Thus, as the

shaft 128 and disk 140 rotate, engagement of the tap bolt in the slot 132, will cause the lever 133 to rock back and forth about its pivot 134. At its upper end, the lever 133 is flexibly connected to a transversely extending rod 135 by a link 136. The rod 135 is mounted in grooves 137 formed in the nozzle block 109 and is free to reciprocate as the free end of the lever travels back and forth. The rod 135 is provided with the racks 138 which engage with teeth 139 on the outer surface of the curved upstanding trough walls 116 whereby the troughs 112 are oscillated as reciprocation of the rod 135 occurs.

I claim:

1. A stoker for a plurality of furnaces arranged side by side, each of said furnaces having a furnace front provided with a firing opening, said stoker comprising a fuel feed conduit spaced from and extending along said furnace fronts substantially at the level of the lower margin of said firing openings, a screw conveyor in said conduit for advancing fuel therethrough, a plurality of feed devices, each of said devices communicating at one end with said conduit for receiving fuel therefrom and communicating at their respective other ends with a respective firing opening, said feed devices each including an upright conveyor screw for elevating fuel to a respective firing opening, means for raising and lowering said upright conveyor screws for varying the amount of fuel delivered to said firing openings by said upright conveyor screws, and means at said openings for projecting fuel into said furnaces in aerial paths.

2. A stoker for a plurality of furnaces arranged side by side, each of said furnaces having a furnace front provided with a firing opening, said stoker comprising a fuel feed conduit spaced from and extending along said furnace fronts substantially at the level of the lower margin of said firing openings, a screw conveyor in said conduit for advancing fuel therethrough, a plurality of feed devices, each of said devices communicating at one end with said conduit for receiving fuel therefrom and communicating at their respective other ends with a respective firing opening, said feed devices each including an upright conveyor screw for elevating fuel to a respective firing opening, means for raising and lowering said upright conveyor screws for varying the amount of fuel delivered to said firing openings by said upright conveyor screws, and means at said openings for projecting fuel into said furnaces in aerial paths.

3. A stoker for a plurality of furnaces arranged side by side, each of said furnaces having a furnace front provided with a firing opening, said stoker comprising a fuel feed conduit spaced from and extending along said furnace fronts substantially at the level of the lower margin of said firing openings, a discharge conduit communicating with each of said firing openings and arranged to receive fuel from said fuel feed conduit, said discharge conduits having an open upper end and terminating at said upper end adjacent the bottom of a respective firing opening, a door for each of said firing openings, said doors each having an outwardly bulged portion surmounting the open upper end of a respective discharge conduit, means in each of said conduits for conveying fuel therethrough and means at said firing opening for projecting fuel into said furnaces in aerial paths.

4. A stoker for a plurality of furnaces arranged side by side, each of said furnaces having a furnace front provided with a firing opening, the combination of a fuel feed conduit spaced from and extending along said furnace fronts substantially at the level of the lower margin of said firing openings, a discharge conduit communicating with each of said firing openings and arranged to receive fuel from said fuel feed conduit, said discharge conduits having an open upper end and terminating at said upper end adjacent the bottom of a respective firing opening, a door for each of said firing openings, said doors each having an outwardly bulged portion surmounting the open upper end of a respective discharge conduit, means in each of said conduits for conveying fuel therethrough and means at said firing opening for projecting fuel into said furnaces in aerial paths.

4. In a plurality of furnaces arranged side by side, each of said furnaces having a furnace front provided with a firing opening for conjoint manual and mechanical firing, the combination of a fuel feed conduit spaced from and extending along said furnace fronts substantially at the level of the lower margin of said firing openings, a plurality of discharge conduits, each of said conduits communicating with a respective firing opening and arranged to receive fuel from said fuel feed conduit, said discharge conduits having an open upper end and terminating at said upper end adjacent the bottom of a respective firing opening, a door for each of said firing openings, said doors having an outwardly bulged portion surmounting the open upper end of a respective discharge conduit, a screw conveyor in said fuel feed conduit for conveying fuel therethrough, an upright screw conveyor in each of said discharge conduits for elevating fuel therethrough and forcing it through the bulged portion of the door into the firing opening, and means at said firing opening for projecting fuel into said furnaces in aerial paths.

5. In a plurality of furnaces arranged side by side, each of said furnaces having a furnace front provided with a firing opening for conjoint manual and mechanical firing, the combination of a fuel feed conduit spaced from and extending horizontally along furnace fronts substantially at the level of the lower margin of said firing openings, a plurality of discharge conduits, each of said conduits communicating with a respective firing opening and arranged to receive fuel from said fuel feed conduit, said discharge conduits having an open upper end and terminating at said upper end adjacent the bottom of a respective firing opening, a door for each of said firing openings, said doors having an outwardly bulged portion surmounting the open upper end of a respective discharge conduit, a screw conveyor in said fuel feed conduit for conveying fuel therethrough, an upright screw conveyor in each of said discharge conduits for elevating fuel therethrough and forcing it through the bulged portion of the door into the firing opening, and means at said firing opening for projecting fuel into said furnaces in aerial paths.

6. A stoker for feeding fuel to a plurality of

laterally spaced furnace firing openings comprising a fuel conduit having a fuel discharge opening below the level of each of said firing openings, said conduit having a fuel receiving opening at one end thereof communicating with a source of fuel supply, means in said conduit for conveying fuel therethrough from said receiving end to each of said discharge openings, a plurality of fuel feed devices, each of said fuel feed devices providing communication between a discharge opening of said fuel conduit and a firing opening, said feed devices each including an upright conveyor screw for elevating fuel to a respective firing opening, and means for raising or lowering said upright conveyor screws for varying the amount of fuel delivered to said firing openings by said upright conveyor screws.

7. A stoker for feeding fuel to a plurality of laterally spaced furnace firing openings comprising a fuel feed conduit having a fuel discharge opening subjacent each of said firing openings and a fuel receiving opening at one end thereof, a riser conduit communicating at its upper end with the fuel receiving opening of said fuel feed conduit, a plurality of feed devices, each of said feed devices providing communication between a discharge opening of said fuel feed conduit and a firing opening, a screw conveyor in said fuel feed conduit and a screw conveyor in said riser conduit, means operatively connected to the lower end of said riser conduit screw conveyor for actuating the same, said screw conveyors being provided with shaft extensions projecting through the adjacent ends of their respective conduits, means associated with said shaft extensions for operating the fuel feed conduit screw from the riser conduit screw, an upstanding screw conveyor in each of said fuel devices for elevating fuel to a respective firing opening, a shaft extending along the lower ends of said feed devices to a point adjacent said screw shaft extensions, means operatively connecting the adjacent ends of said shaft and one of said screw shaft extensions, said upstanding screw conveyors each having a shaft extension projecting through the bottom of said feed devices and means operatively connecting each of said last named screw shaft extensions with said shaft.

NATHAN M. LOWER.
